(57) **CLAIM**

The ornamental design for a mount for packaging of battery, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of the mount for packaging of battery showing a first embodiment of our new design;

FIG. 2 is a rear view thereof;

FIG. 3 is a left side view thereof, the right side view is identical thereto;

FIG. 4 is a top plan view thereof, the bottom view is identical thereto;

FIG. 5 is a cross sectional view thereof, taken in the direction of line 5—5 in FIG. 1;

FIG. 6 is a front view of the mount for packaging of battery showing a second embodiment of our new design;

FIG. 7 is a rear view thereof;

FIG. 8 is a left side view thereof, the right side view is identical thereto;

FIG. 9 is a top plan view thereof, the bottom view is identical thereto; and,

FIG. 10 is a cross sectional view thereof; taken in the direction of line 10—10 in FIG. 6.
